FRAME

Harry M. Magid, Chicago, Ill.

Application July 1, 1932. Serial No. 620,400

6 Claims. (Cl. 40—125)

My invention relates to a support for signs and the like, and more particularly to a frame support which can be used with transparent signs, shadow boxes, pictures, or designs to be viewed from two sides, and which is adaptable to a double-faced sign to be viewed from two sides, and to hold signs or other displays made of flimsy material as well as heavy stiff material.

An object of my invention is to provide a frame 10 having a means for securely fastening its corners and for holding the frame in spaced relation from a support and having a further means surmounted on the fastening means for adhesively fastening the frame to a support.

15 Another object of my invention is to provide a sign-supporting frame the construction of which is adaptable to many sizes, weights, and shapes without departing in any material measure from that shown or described herein, and one which 20 when assembled forms a frame, not only relatively light in weight and remarkably compact, but one which is as well substantially durable, strong and somewhat more flexible than the conventional form of wooden frame.

25 Another object of my invention is to provide a construction adaptable to being produced of laminated material, thereby obtaining the usual and some special advantages of that type of construction over that wherein each of the parts is 30 made from a single piece of material.

A further object of my invention is to provide a laminated construction in a frame which permits the use of overhanging laminations to form a groove, thereby avoiding the use of mortising 35 machinery, and, at the same time, effecting a stronger construction through having the overhanging edges form the groove. These features are especially prominent when the overhanging plies are of relatively thin, tough material such 40 as metal, presenting a structure of minimum thickness and maximum strength.

45 A still further object of my invention is to provide composite laminations in the construction shown and described, in which the middle or axial plies are of a relatively light-weight material and relatively thick compared with the outer plies, which outer plies would be made of relatively high-tensile strength material such as metal. Such construction would have a relatively high bending stress depending substantially upon the distance away from the center 50 the metal would be positioned.

An object of my invention is in providing a construction only slightly different in appearance 55 from either side, making it adaptable to signs having front and back displays.

My invention has for an object the provision of a slidably replaceable mounting having a means thereon for holding flat a sign or display 60 of flimsy material.

In my invention another object is in providing a method wherein a frame or similar device, having pieces of nitrocellulose fastened thereon, can be fastened to glass or other support with a strong transparent adhesive. A valuable feature of this 65 method is that when the frame or device is pried from its support no unsightly blemish or mark of any kind remains to be removed from the support.

A still further object of my invention is to provide a strong corner construction. The weakest part of a frame or similar structure is well known to be its corners. In order then to overcome this handicap I have provided a scarf joint at the corners by overlapping them and fastening thereto a piece of material serving not 70 only to strengthen and support the construction at the corners but also for ornamental purposes.

Another object in my invention is in providing a means for fastening the frame to a support, a means which can be distributed to any part 80 of the frame depending upon the weight and the position of the weight which it must carry, yet without detracting from its appearance. If effectively distributed these means add considerably in ornamental value to a frame.

85 A further object of my invention is in providing a means for fastening the device to a support in any position or angle depending upon the position and angle of the support.

Another object of my invention is in providing 90 a construction materially free from warpage.

Other objects and advantages will hereinafter be more fully pointed out, and for a more complete understanding of the characteristic features of this invention reference may now be had to the following description when taken together with the accompanying drawing, in which latter:

Figure 1 is a perspective view of my invention 100 in place on a display window.

Fig. 2 is a view showing constructional details 100 in perspective.

Fig. 3 is a perspective drawing of an alternative form of mounting for holding flexible sheets.

In referring more particularly to the drawing, Figure 1 depicts how the frame 10 can be applied to a show case or window 12, which arrangement is adapted to display one or two sides of a sign 13 held in position by recess-forming strips 14.

110 Fig. 2 shows the details of construction of the frame 10 and inserted mounting 15. The sides of the frame are composed of an inner lamination 16 of relatively thick but light-weight material such as wood, and adhesively fastened to each of the back and front faces is a relatively thin and high tensile-strength laminated material 17 extending up to the corner plates 18 and up to the reduced portion 19 of cross-piece 20. Corner plates 18 overlap and cement together 120

the mitred corners of inner lamination 16 forming a substantial fastening. The reduced portions 19 of cross-piece 20 are cemented to inner lamination 16 of the sides and serve as a firm binding for the two opposite sides. The outer plies 17 of the sides extend inwardly beyond the inner edge of the inner ply 16 to form a groove for slidably inserting the mounting 15. The mounting 15 is composed of a relatively stiff member 21 and the formed transparent strip 14 cemented along three of its edges to form a recess to accommodate a paper or other similar insert 13. Blocks 23, cemented upon the plates 18 and upon the reduced portions 19 of cross-piece 20, are of nitrocellulose and form a means, through the application of a transparent cementing medium, for fastening the frame 10 to a support 12 as shown in Fig. 1.

Fig. 3 is a broken detailed view showing another arrangement of mounting member 21 by which two display sheets 13 can be accommodated, one on each side, by the use of another form of recess-forming strip 14a cemented to mounting member 21.

In the use of my invention the nitrocellulose blocks are subjected to an application of a retardent nitrocellulose solvent which leaves the surface of the blocks sufficiently viscous to adhere to smooth surfaces with which it comes in contact. It adheres very effectively to glass and is capable of sustaining reasonably heavy weights. When the frame is to be removed for other uses the corners can be readily pried away from their supports without damaging the frame and without leaving traces of the solvent or nitrocellulose blocks, obviating, therefore, the necessity of the usual scraping of adhesives from supports. The blocks being of ornamental design and color, and being covered by a transparent solvent to produce cementing qualities, leave a neat and effective appearance.

Not only is the sign itself readily detachable from its support, but the mounting member as well as the display sheet itself are slidably removable. The corners of the frame are constructed to allow the fingers to secure a grip for pulling the adhering blocks from their support. The relatively small size of the blocks allow relatively high pressure per unit area to be exerted from the back of the frame when mounting.

Further modifications will be apparent to those skilled in the art and it is desired, therefore, that the invention be limited only by the prior art and the scope of the appended claims.

Having thus described my invention, what I claim and desire to secure by Letters Patent is:

1. A frame, a plurality of spacing means distributively mounted on said frame, and ornamental pieces of nitrocellulose surmounted on said spacing means for adhesively fastening said

frame to a support by the use of a nitrocellulose cement.

2. A frame comprising a plurality of sides having along one edge thereof a groove, said sides being joined at their ends to form a frame, a relatively thin cross-piece connecting the ends of two opposite sides, said cross-piece being sufficiently offset to allow unobstructed access to said grooves, combined spacing and fastening means for respectively spacing said frame from its support and for fastening together the two ends of said sides disposed to form a frame, and a fastening means surmounted on said spacing means for fastening said frame to a support.

3. A frame comprising a plurality of sides having along the inner edge thereof a groove, a reduced portion at the end of said sides, said reduced portion being mitred and joined endwise to its adjacent side to form a frame, a flat plate covering said reduced portion and mitred joint and fastening rigidly together the two adjacent sides, and spacing said frame from a window or other support, a fastening means attached to said plates, and a relatively thin cross-piece joining two sides, said cross-piece being offset to allow unobstructed access to said grooves, said cross-piece having at its two ends a reduced portion for fitting onto said reduced portion of two opposite sides and being fastened thereto.

4. A laminated frame comprising a plurality of laminated sides having along one edge thereof a groove, said sides comprising a plurality of inner and outer plies, said inner plies being mitred and joined at their ends to form a frame, said outer plies extending somewhat short of the ends of said sides to form a reduced portion for a fastening and spacing means, a fastening and spacing means comprising a plate overlapping the ends of two adjacent sides, a further fastening means surmounted on said fastening and spacing means for adhesive attachment to a support, and a laminated cross-piece of relatively thin construction.

5. A frame including a plurality of sides, a plurality of combined spacing and fastening means for respectively spacing said frame from its support and for fastening together the ends of said sides to form a frame, and pieces of nitrocellulose surmounted on said spacing and fastening means for adhesively fastening said frame to a support by the use of nitrocellulose solvent applied to said pieces of nitrocellulose.

6. A frame, means for securely fastening together the sides of said frame, and a nitrocellulose combination spacing and fastening means surmounted on said first means for respectively spacing and adhesively fastening said frame to a support.

HARRY M. MAGID.
